UNITED STATES PATENT OFFICE.

ANTON I. SANDBO, OF ROCK ISLAND, ILLINOIS.

SAFETY CRANKING DEVICE.

1,333,186.

Specification of Letters Patent.

Patented Mar. 9, 1920.

Application filed March 25, 1919. Serial No. 284,898.

To all whom it may concern:

Be it known that I, ANTON I. SANDBO, a citizen of the United States, residing at Rock Island, in the county of Rock Island 5 and State of Illinois, have invented certain new and useful Improvements in Safety Cranking Devices; and I do hereby declare the following to be a full, clear, and exact description of the invention, such as will 10 enable others skilled in the art to which it appertains to make and use the same.

The present invention relates to a safety device for use with cranks employed for starting the internal combustion engines of 15 automobiles, and is particularly an improvement over the safety cranking device disclosed in my Patent No. 1,288,448, granted Dec. 17, 1918.

The invention has for its object the provision of a novel and improved attachment 20 for engine stopping cranks, and so constructed and operable in order that when the engine back fires, this will automatically disconnect the crank from the engine crank 25 shaft, thereby avoiding injury to the operator, as not infrequently happens, with the use of the ordinary crank.

As a more specific object, the invention aims to improve the device disclosed in said 30 patent, to enhance the utility and efficiency of the appliance.

With the foregoing and other objects in view which will be apparent as the description proceeds, the invention resides in the 35 construction and arrangement of parts hereinafter described and claimed, it being understood that changes can be made within the scope of what is claimed without departing from the spirit of the invention.

40 The invention is illustrated in the accompanying drawing, wherein:—

Figure 1 is a front view of the device as applied, a portion of the starting crank being broken away.

45 Fig. 2 is a cross section through the drum and ring showing the ratchet between them.

Fig. 3 is a side elevation of the device.

Fig. 4 is a vertical diametrical section.

50 Fig. 5 is a plan view of the yoke for controlling the movement of the ring.

In the drawings, there is shown the starting crank 1 of an automobile engine, which is mounted for rotary and sliding movements in a bearing 2 that is secured on the frame by means of bolts 3 having the nuts 4 thereon. The rear end of the crank 1 has

5 a ratchet clutch member 5 to move rearwardly and engage the clutch pin 6 of the engine crank shaft 7 as usual, so that by shifting the crank rearwardly and turning 60 it, the engine can be started. However, in the event that the engine back fires, this will spin the crank 1 rearwardly, which has frequently resulted in injuries and annoyances.

The safety device includes a drum 8 designed to be secured on the shaft or spindle portion of the starting crank 1, and said drum 8 may be provided with different means for attaching it to the starting crank, according to the construction of said crank. 70 As shown, the drum 8 has a central opening 9 through which the crank 1 projects, and a clamping member 10 shaped to fit the bend of the crank, is secured to the drum 8 by means of screws 10 or the like, thereby 75 securing the drum firmly to the crank to rotate therewith, although other means can be employed to secure the drum in place as disclosed in said patent. A disk or plate 12 is secured to the forward side of the 80 drum 8 between the clamping member 10 and said drum, and may form part of the clamp which embraces the crank, the edge of said plate projecting beyond the periphery of the drum, as seen in Fig. 4.

A ring 13 surrounds the drum 8 and is mounted for limited oscillatory movement, while the drum is rotatable within said ring with the crank. The forward edge of the ring 13 has a rabbet 14 receiving the edge 90 of the plate 12, while the rear edge of the ring 13 has an inwardly extending annular flange 15 fitting rotatably on the drum 8 against the shoulder 16 thereof. In order to retain the ring 13 on the drum, a split 95 resilient ring 17 can be snapped into and an annular groove 18 in the drum behind the shoulder 16 and flange 15, or other suitable means can be used for this purpose. It will therefore be noted that the ring is 100 mounted for oscillation on the drum and is supported thereby.

A ratchet is provided between the drum and ring, permitting the drum to rotate with the crank in starting the engine, but causing 105 the ring to rotate reversely with the drum, in case of back firing, so that this will result in the disengagement of the clutch member 5 from the pin 6, as will hereinafter more fully appear. This ratchet includes ratchet recesses 19 in the interior of the ring 13 and similar recesses 20 in the periphery of

the drum, and rollers 21 constituting dogs or pawls disposed in the recesses 19 at that side of the drum and ring where said rollers will drop by gravity away from the deeper 5 ends of the recesses so as to wedge between the inclined or cam walls of said recesses of the drum and ring as seen in Fig. 2. This side of the drum and ring is termed the gravity side, because the rollers fall by grav- 10 ity to bind between the drum and ring, and the recesses 19 are smaller than the recesses 20 and in irregular arrangement relatively thereto, so that whenever the drum 8 re- 15 verses, one of the rollers 21 will be in position to bind instantly between the drum and ring, causing the ring 13 to rotate reversely with the drum, without any lost motion or loose play. The rear ends of the rollers 21 abut the flange 15 and their forward end 20 abut the plate 12.

In order to control the movement of the ring 13, said ring is provided at opposite sides with outstanding studs 22 on which rollers 23 are mounted for rotation, and an 25 arcuate depending yoke 24 is hung below the axis and is provided at its ends with outstanding aperture ears 25 to engage over the bolts 3 and be clamped in place by the nuts 4, thus enabling said yoke to be easily 30 applied. This yoke has abutments 26 against which the rollers 23 normally bear rearwardly when the crank is in normal position, and said yoke has inclined cams 27 extending helically rearward from said 35 abutments. Thus, when the crank 1 is turned and moved rearwardly, the rollers 23 can roll from the abutment 26 along the cams 27 to bring the clutch member 5 into engagement with the pin 6, the ring 15 being shifted with the drum 8 and crank 1 during such movement. In order to limit the oscillatory movement of the ring 13, the lower portion of the yoke 24 has a forwardly extending loop 28 projecting under 40 the ring 15, and said ring has a depending lug 29 working within said loop, thereby only permitting the ring to turn the distance between the ends of the loop 28 when the lug 29 will contact therewith.

50 The yoke 24 can be provided with apertured ears or lugs 30 at the opposite ends of the loop 28 for the suspension of a license tag 31 as seen in Fig. 1, thus providing an additional advantage for said yoke.

55 In operation, when the crank 1 is shifted rearwardly, the ring 13 being turned slightly so that the rollers 23 can move rearwardly along the cam 27, the drum and ring will be shifted rearwardly, and when 60 the clutch member 5 engages the pin 6, the crank can be turned in the usual way for starting the engine. When the crank is released, it is moved forwardly out of engagement with the engine crank shaft by the 65 spring provided for that purpose. The

function of the present device is to automatically disconnect that starting crank from the engine shaft in the event that the engine back fires. Thus if this occurs, thereby rotating the drum 8 reversely with the 70 crank 8, one of the rollers 21 will instantly bind between the drum and ring 15 thereby rotating said ring back with the drum and the rollers 23 in contacting with the cam 27 will force the ring 15 forwardly by cam 75 action thereby shifting the drum 8 and crank 1 likewise and automatically disconnecting the clutch member 5 from the pin 6. This disconnection will take place the moment the crank 1 starts to move reversely 80 with the engine shaft, thereby avoiding possible injury to the operator.

Having thus described the invention, what is claimed as new is:

1. A safety cranking device including a 85 drum adapted to be secured on an engine starting crank, a ring surrounding the drum, means for shifting said ring and drum to disconnect said crank from an engine shaft when said ring rotates reversely, the interior 90 of the ring and periphery of the drum having ratchet recesses of different sizes and irregular arrangement, and rollers in the recesses of the ring to drop by gravity away from the deeper ends of said recesses of the 95 ring, and drum to bind between the inclined walls thereof.

2. A safety cranking device including a 100 drum adapted to be secured on an engine starting crank, a ring surrounding the drum, a ratchet means between said drum and ring, and a yoke having portions at its ends for attachment to an automobile frame and having cams at its ends, said ring having 105 portions to engage the cams to shift said ring forwardly when it is rotated reversely with the drum, said ring and yoke having means for limiting the oscillation of the ring.

3. A safety cranking device embodying a 110 drum adapted to be secured on an engine starting crank, a ring surrounding the drum and shiftable therewith, ratchet means between said drum and ring to rotate the ring reversely with the drum, and an arcuate 115 yoke having portions at its ends for attachment to an automobile frame and having cams at said ends and a loop between its ends, said ring having a lug working within said loop to limit the oscillation of the ring, and having opposite rollers to engage said cams and shift the ring and drum forwardly when the ring is rotated reversely.

4. A safety cranking device embodying a 125 drum adapted to be secured on an engine starting crank, a ring surrounding the drum, ratchet means between said ring and drum to rotate the ring reversely with the drum, and a yoke having means at its ends for attachment to an automobile frame, said 130

ring and yoke having coöperating means for shifting the ring and drum forwardly when the ring is rotated reversely, said yoke having portions for supporting a license

5 tag.

5. A safety cranking device embodying a drum adapted to be secured on an engine starting crank, a plate secured to the front side of the drum, a ring surrounding the

10 drum and having its forward edge fitting the edge of said plate, said ring having an inturned annular flange at its rear edge mounted rotatably on the drum, means on

the drum in rear of said flange to hold the ring thereon, ratchet means between said 15 ring and drum, and means for shifting said ring to disengage the starting crank when said ring rotates reversely with the drum.

In testimony whereof I have signed my name to this specification in the presence of 20 two subscribing witnesses.

ANTON I. SANDBO.
